UNITED STATES PATENT OFFICE.

LINNAEUS E. BAKER, OF FORT WAYNE, INDIANA, ASSIGNOR TO WAYNE OIL TANK AND PUMP COMPANY, OF FORT WAYNE, INDIANA, A CORPORATION OF INDIANA.

MECHANICAL CUT-OUT FOR FLOAT-METERS.

1,393,421.

Specification of Letters Patent. Patented Oct. 11, 1921.

Application filed December 16, 1919. Serial No. 345,417.

To all whom it may concern:

Be it known that I, LINNAEUS E. BAKER, a citizen of the United States, residing at Fort Wayne, in the county of Allen and 5 State of Indiana, have invented new and useful Improvements in Mechanical Cut-Outs for Float-Meters, of which the following is a specification.

My invention relates to float meters, and 10 particularly to means for disengaging the rack from the gear that meshes therewith to actuate the indicating and registering mechanism.

Under some conditions containers having 15 float meters must be emptied back into the storage tank or other source of supply instead of the liquid being dispensed to the customer's tank or other point of usual delivery; and as the meter is to register and 20 indicate the liquid dispensed not including that returned to storage, cut-out mechanism to prevent the operation of the meter is necessary in such cases. My invention provides such mechanism.

25 My invention is illustrated in the accompanying drawings in which:—

Figure 1, is a sectional elevation of an elevated container for liquid, exposing to 30 view a float meter and its upright rack in position to operate the meter,

Fig. 2, is the same with the drain back valve open and the rack withdrawn from meshing contact with the rack gear of the meter; so as to cut-out the meter from operation,

Fig. 3, is a cross section on the line 3—3 of Fig. 1, as though the container was there shown in full, and

Fig. 4, is a cross section on the line 4—4 of Fig. 2, as though the container was there shown in full.

Referring now to the drawings; A, is the cylinder of an elevated container usually made of glass or provided with windows, a, is the container bottom and a¹, is the top, these parts being suitably connected by tie-rods a². The container is mounted upon a pedestal P.

B, is the discharge pipe vertically slid- 50 able through the stuffing box a³.

C, is the fill pipe and D, the overflow pipe fixed in position within the container.

A drain-back orifice E, is provided in the bottom of the container to carry back to

the storage tank the contents of the container when so desired, as when locking up the apparatus for the night. A needle valve e, guided by the bracket e¹, is adapted to keep the orifice E, normally closed and to be raised to open position by manipulation of the lever e², being pivoted thereto by a screw e³, provided to adjust the length of the needle valve element. This screw e³, is left protruding from the upper end of the needle valve e, a distance sufficient to allow some upward movement of the lever e², before lifting the needle valve e, from its seat in the orifice E, for a purpose hereafter to be described. The lever e², is pivoted at e⁴, to a bracket a⁴, on the container top a¹. The free end e⁵, of the lever e², is adapted to contact with and be raised by the top of the discharge pipe B, when raised to drain back position. Obviously the lever e², may be operated in any other convenient manner.

A float meter F, with a suitable rack gear f, is adapted to operate the meter f¹, only while the float is descending.

The gear f, is normally in mesh with the teeth of the rack F¹, at all times during operation of the apparatus. The guide bars f², f³, are fixed to the top a⁴, and the bottom a, of the container, and are so spaced that the rack F¹, is free to move between them within the limits allowed by pins f⁴, f⁵, fixed in the bars f², f³, and free in the parallel diagonal slots f⁶, f⁷, in the rack F¹.

A connecting rod f⁸, is pivoted at one of its ends to the back of the rack F¹, and at its other end to the lever e², in such a manner that before the needle e, is lifted to open the orifice E, the rack F¹, will be withdrawn from meshing position with the pinion f, so that the float meter descends with the body of liquid when the liquid is being drained back to storage with the meter not registering.

When the lever e², is lowered the needle e, closes the orifice and thereafter the connecting rod f⁸, slides the rack F¹, into operative position with the pinion f, all by gravity.

Whatever means will produce disengagement of the rack and its pinion during that movement of the float meter on which normally metering occurs, is within the scope of my invention.

I claim as my invention and desire to secure by Letters Patent of the United States:

1. In combination with a float meter having a rack gear, fixed upright guiding means upon which said float meter rises and falls, an upright rack adapted to mesh with the rack gear while the meter is in operation, and means for moving the rack backwardly out of mesh with the rack gear when metering is to be avoided. 25
2. In combination with a float meter having a rack gear, two fixed upright parallel guides upon which the float meter rises and falls, an upright rack movably mounted between said guides and means for moving the rack backwardly to throw it out of mesh with the rack gear and forward into mesh again. 30
3. In combination with a float meter having a rack gear, two fixed upright parallel

guide bars upon which the float meter rises and falls, an upright rack movable between said guide bars, parallel oblique guides for said rack to permit its backward movement 25 parallel with the guide bars, and means for producing said movement of the rack.

4. In combination with a float meter having a rack gear, two fixed upright parallel guide bars upon which the float meter rises 30 and falls, a rack between the guide bars having guiding means fixed to the guide bars and piercing the rack to permit simultaneous backward and upward movement of the rack, and means for so moving the rack. 35

In testimony whereof I have hereunto set my hand in presence of two subscribing witnesses.

LINNIEUS E. BAKER.
